COMPARTMENT BOX AND ASSEMBLY FOR
USE THEREIN

Joseph J. Dombroski, Providence, R. I.

Application November 16, 1935, Serial No. 50,173

12 Claims. (Cl. 229—10)

My invention relates to improvements in compartment boxes of the type adapted for use with small articles, such as candy, nuts, cigars, dentists' tools, jewelry, etc. and preferably provided with means for the ready selective dispensing therefrom of different types of articles.

A further object of my invention is to provide a box constructed entirely of cardboard, paper and corrugated board which may be readily assembled in a facile and relatively cheap manner.

A further object of my invention relates to improvements in the knob means for each drawer and the provision of means to prevent the knob means from sticking through an exterior layer 15 of wrapping material.

A further object of my invention is to provide a box assembly which entirely eliminates any fastening means to join the interior parts thereof together and which therefore may be more 20 quickly assembled.

A further object of my invention is to provide a compartment box comprising a plurality of tiers of drawer compartments which may be built up if desired to any desired number of tiers and 25 further if desired of any desired number of horizontally arranged individual drawer compartments in each tier.

A further object of my invention is to provide a compartment box to receive drawers in 30 which during the assembly thereof the different parts thereof become automatically self-aligned.

A further object of my invention due to the inherent compressibility of the layers of corrugated board and the pivotable end wall for each 35 drawer compartment I preferably employ is to provide means to automatically grip each drawer when inserted and retain it in a closed or open position.

A further object of my invention is to provide 40 a compartment box which may be readily sold as a unit and on which selective plaques may be readily inserted bearing the advertising matter of a selected vendor and a further object of my invention is to at all times display the advertising matter of the vendor even when the box 45 is being used as there is no pivoted or removable cover as in ordinary types of candy boxes and it is apparent that advertising matter on 50 the top thereof will be continuously displayed even as each drawer is opened for dispensing purposes.

These and such other objects of my invention as may hereinafter appear will be best understood 55 from a description of the accompanying

drawings, which illustrate an embodiment thereof.

In the drawings, Fig. 1 is a perspective view, with a corner thereof partially broken away to show the interior construction thereof, of a compartment box constructed in accordance with my invention with one drawer removed and one drawer partially open. 5

Fig. 2 is a plan view of the cardboard cover blank I preferably employ as the cover for my 10 improved box.

Fig. 3 is a perspective view showing the assembly of tiers of drawer compartments and layers of corrugated board spacing layers each built up to the desired height and prior to the 15 insertion of the cover therearound.

Fig. 4 is a plan view of the blank I preferably employ in the manufacture of each drawer compartment.

Fig. 5 is a perspective view of the blank shown 20 in Fig. 4 infolded to form a drawer compartment.

Fig. 6 is a plan view of the blank I preferably employ in making up each respective drawer.

Fig. 7 is a section taken through the center 25 of a drawer showing the opposite half of the drawer in perspective.

Fig. 8 is a front view of the supplemental cardboard strip of greater area than the drawer front wall that I preferably secure thereto.

Fig. 9 is a front elevation of a partially assembled box showing the supplemental cardboard strips of greater area than the top of said box about to be secured thereto and the supplemental plaque adapted to contain advertising matter distinctive of each individual vendor adapted to 30 be supplementally secured to the top thereof. 35

Fig. 10 is a side elevation partially shown in section of the improved knob means I preferably employ for each drawer.

Fig. 11 is a disassembled perspective view showing the disassembled parts of my improved knob means. 40

In the drawings, wherein like characters of reference indicate like parts throughout, 12 generally indicates a compartment box constructed 45 in accordance with the teachings of my invention. The construction of my improved box will probably be best understood if it be described in accordance with its method of manufacture.

As the cover for my improved box I preferably 50 employ a continuous cardboard strip 14 comprising the base 16, a rear wall 18 projecting rearwardly from said base adapted to be infolded upwardly along the fold line 20 to form the rear wall of said cover, the end walls 22 projecting 55

integrally laterally from said base adapted to be infolded upwardly along the respective fold lines 24 to form the box end walls, and a front wall 26 projecting integrally forwardly from said base 5 adapted to be infolded upwardly along the fold line 28 to form the front wall of said box having a plurality of tiers, in the embodiment shown, an upper tier 30^a and a lower tier 30^b, of drawer holes therein, in the embodiment shown, the plurality of horizontally aligned drawer holes 32^a forming the upper tier 30^a and a single drawer hole 32^b forming said lower tier 30^b and a top 34 projecting integrally forwardly from said front wall 26 adapted to be infolded along the fold line 36 over said box to form the top wall thereof and to have the end 38 abut the upper end of said rear wall 18 when arranged in assembled position.

I also employ a plurality of oblong hollow drawer compartments 40 having an interior of substantially the size of said drawer holes 32^a and 32^b respectively and of substantially the depth of said box each comprising a continuous piece of cardboard 40 having at one end thereof the base 42 and projecting continuously laterally from one end thereof an end wall 44 adapted to be infolded upwardly along the fold line 46 to form a drawer compartment end wall, the top portion 48 continuous with the end of said end wall 44 adapted to be infolded over said base along the fold line 50 to form the top of said drawer compartment and the end wall 52 integral and continuous with said top adapted to be infolded downwardly along the fold line 54 to form the opposite end wall of said drawer compartment and to pivot in use along said fold line 54, if it be desired to employ the automatic drawer-retaining feature of my invention later to be described, if not having the end thereof 40 adapted to be permanently secured to the opposite end of said base.

As shown I also employ layers 56 of compressible strip spacing material adapted to be interposed horizontally and vertically between the cover base, top and end walls and each respective compartment base, top and end walls in each tier and also between the tiers and drawer compartments in a single tier to build up an assembly to make up the interior of the box of a size slightly greater than the interior of the box. While any suitable type of layers of compressible strip spacing material if desired of different thickness may be employed for this purpose, I preferably employ a corrugated board, which of itself is inherently somewhat compressible, although other types of compressible strip spacing material, such as felt, wadding, paper, etc. may be employed. The respective tiers 58^a and 58^b of drawer compartments 40 are arranged one above the other 60 and if a plurality of horizontally aligned drawer compartments be employed they are suitably horizontally aligned and the layers of strip material suitably inserted above, below and intermediate said tiers and at the respective outer end 65 of each compartment box in each tier and in between the respective drawer compartments in a tier. In the preferred embodiment, the lower tier 58^b consists entirely of an enlarged drawer compartment 40^b and the upper tier 58^a consists 70 of the smaller horizontally aligned drawer compartments 40^a and 40^{a'}. These, however, are first assembled from the bottom up and as shown in Fig. 3 I lay a plurality of layers 62 of corrugated board of the length and depth of the box 75 on a base and superimpose thereon the enlarged

lower drawer compartment 40^b. I then lay a plurality of thin elongated layers or strips of corrugated board 64 exterior of the outer ends of the drawer compartment 40^b. In the embodiment shown the outer respective layer 66 is 5 thicker than the inner respective layer 68 and I thus may selectively employ the desired number of layers of strip material to build up the composite box to the desired size and to accurately align the front ends of each respective drawer compartment with the respective drawer holes 32^a and 32^b in the cover when assembled and I may selectively employ layers of corrugated board of different thicknesses so as to build the box structure up substantially to its desired size. I 10 then superimpose on top of the compartment box 40^b the desired number of layers or spacing strips of corrugated board 70 to space the respective ends of the drawer compartments 40^a and 40^{a'} substantially opposite the drawer holes 32^a in 15 the cover. I then interpose the desired number of spacing strips 72 of the proper thickness between the drawer compartments 40^a and 40^{a'} to horizontally align the respective ends thereof with the drawer holes 32^a and I add at the outer 20 ends of the respective drawer compartments the desired number of spacing strips 74, in this instance with the inner layer 78 thereof of less thickness than the outer layer 80. I then superimpose on top of the upper drawer compartments 30 40^a and 40^{a'} the desired number of spacing layers 82 of strip material to build the assembly shown in Fig. 2 up to the desired size, the whole assembly both vertically and horizontally being 35 preferably of slightly greater area than the desired box so that when the cover 16 is mounted therearound the spacing layers may be compressed to the desired size of the box to provide a finished box which will not rattle and to bring the front ends of the drawer compartments accurately in alignment with the respective drawer holes in the cover. Thus the assembly shown in Fig. 3 is inserted over the base 16 of the cover shown in Fig. 2, the respective rear and side walls bent upwards, the front wall bent upwards 45 and the top wall bent over the assembly to compress the box to the desired size for the above-mentioned purposes.

I then provide means to bind said cover around the walls of said box to maintain said drawer compartments and spacing layers together as the interior of a unitary box. The respective ends of the respective walls of the cover may be attached together by glue if desired, but I may suitably secure the walls of the cover together around the assembly by individual gummed paper strips, or by wrapping a covering entirely around the exterior of the box and suitably secure it thereto. In my preferred embodiment I preferably employ for this purpose the gummed paper strips 84 and the thin paper covering 85. I also employ cardboard drawers 86 which may be conveniently made from the blanks shown in Fig. 6 by bending the respective front and rear ends and side walls upwardly along the fold lines shown therein and suitably 55 securing them together. The front wall of each respective drawer is preferably provided with a knob hole 88. The drawers 86 are made of a size to fit the respective drawer holes in the cover and when inserted and moved to a closed position 60 within the drawer compartments of a size to be compactly retained therein by the freely pivoted end walls 52 of each respective drawer compartment being urged inwardly by the compressed sheets of strip material.

I also preferably employ the cardboard strips 90 of greater area than the front drawer walls adapted to be secured thereto to overlap the front of the box exterior of the drawer holes for air and dust sealing purposes and to limit the rearward movement of the drawers and having the knob holes 88.

I also employ a preferred type of knob means 92 as the handle of each respective drawer, in my preferred embodiment, comprising the rear portion 94 having a base 96 adapted to abut the rear surface of the wall of each drawer and a tapered shank 97 adapted to project outwardly through the respective holes 88 in the front wall of each 15 drawer and its respective strip 90, and the knob handle portion 98 having the boss 100 projecting rearwardly therefrom adapted to abut the front wall of each drawer or strip 90 where employed to retain or assist in retaining the strips 90 to 20 the front wall of each respective drawer and provided with a central hole 102 therein for frictionally retaining the end of the tapered shank 97 therein to retain said knob means to the drawer. Said knob means may have the portions thereof 25 made of wood, bakelite, pulp, glass or any other suitable material.

To prevent the knob means from sticking through a wrapper when inserted around the box, I also preferably employ the supplemental cardboard strips 104 of greater area than the respective top and bottom of said box so that when the supplemental wrapper is wrapped around said box it will clear the drawer knobs. It is also apparent that the supplemental strips 104 add to the 30 beauty of the finished box.

It is obvious that if desired any desired number of tiers of drawers may be employed, by making the appropriate holes therefor in the cover and employing the suitable number of superimposed tiers of draw compartments and the suitable amount of spacing material. It is also obvious that the number of drawers in each respective tier may be similarly varied.

I also preferably employ a plaque 106 which 45 may have the advertising matter 108 printed thereon distinctive of each individual vendor supplementally selectively secured to the top of said box. It is thus apparent that the boxes may be made up by the manufacturer thereof in quantity and selective plaques inserted thereon as ordered.

It is apparent that with this construction I provide means to positively retain the drawers in closed or open position, the strip material tending 55 to press the pivoted wall 52 of each respective drawer compartment inwardly to abut its respective drawer wall to retain its drawer in its respective open or closed position as left by the user.

It is also apparent that I have provided a novel 60 type of compartment box in which the fastening means for the interior is entirely eliminated and which may be constructed of a minimum number of standard and simple parts, such as cardboard and corrugated board and one which may be 65 readily assembled by the manufacturer with a minimum amount of effort. It is also apparent that I have provided in a candy box, individual compartments for each species of candy, whereby the desired species of candy may be selectively 70 withdrawn without pawing the remainder of the candy and it is further apparent that I have provided a box in which the advertising indicia of the vendor may be continuously displayed in use.

It is understood that my invention is not limited 75 to the specific embodiment shown and that va-

rious deviations may be made therefrom without departing from the spirit and scope of the appended claims.

What I claim is:

1. A compartment box, comprising a continuous cardboard cover comprising a base, a rear wall projecting integrally upwardly from said base, side walls projecting integrally laterally and upwardly from said base, a front wall projecting integrally forwardly and upwardly from said base 10 having a plurality of tiers of drawer holes therein at least one of said tiers having a plurality of horizontally aligned drawer holes therein and a top projecting integrally forwardly from said front wall and over said box of a length to abut the 15 upper end of said rear wall, a plurality of oblong hollow drawer compartments, of substantially the size of said drawer holes, and depth of said box, each comprising a continuous piece of cardboard infolded to form a base, integral end 20 wall, integral top and integral freely pivotable opposite end wall arranged within said cover with the hollow front portion of each one substantially opposite its respective drawer hole, layers of compressible strip spacing material of different thickness 25 interposed horizontally and vertically between said cover base, top, and end walls and each respective compartment base, top and end walls and means to bind said cover around the walls of said box to retain said compartments 30 and layers together, said spacing layers being of a sufficient number and individual thickness that when said cover and binding means are attached around said drawer compartments, said layers 35 may be compressed to accurately retain each respective drawer compartment permanently opposite its respective drawer hole and tend to flex each pivoted compartment end wall inwardly to grip a drawer to retain it therein cardboard drawers each contained within its respective 40 drawer compartment and insertable through its respective drawer hole having a hole centrally thereof, cardboard strips of greater area than the drawer front walls secured thereto for air and dust sealing purposes and to limit the 45 rearward movement of said drawers also having a hole centrally thereof, knob means for said drawers, each comprising a base having a tapered shank projecting outwardly through each drawer and strip hole and a knob handle having a boss 50 projecting rearwardly therefrom adapted to abut the front of each drawer around said hole having a hole therein for frictionally retaining said tapered shank therein, supplemental cardboard strips secured to the top and bottom of 55 said box of greater area than the top and bottom of said box, whereby a supplemental wrapper may be wrapped around said box exterior of said knob means and a plaque adapted to contain advertising matter thereon distinctive of each individual vendor supplementally secured to the top 60 of said box.

2. A compartment box, comprising a continuous cardboard cover comprising a base, a rear wall projecting integrally upwardly from said base, 65 side walls projecting integrally laterally and upwardly from said base, a front wall projecting integrally forwardly and upwardly from said base having a plurality of tiers of drawer holes therein and a top projecting integrally forwardly 70 from said front wall and over said box of a length to abut the upper end of said rear wall, a plurality of oblong hollow drawer compartments of substantially the size of said drawer holes, and depth of said box, each comprising a 75

continuous piece of cardboard infolded to form a base, integral end wall, integral top and integral freely pivotable opposite end wall arranged within said cover with the hollow front portion of each one substantially opposite its respective drawer hole, layers of compressible strip spacing material interposed horizontally and vertically between said cover base, top and end walls and each respective compartment base, top and end walls and means to bind said cover around the walls of said box to retain said compartments and layers together, 10 said spacing layers being of a sufficient number and individual thickness that when said cover and binding means are attached around said drawer compartments, said layers may be compressed to accurately retain each respective drawer compartment permanently opposite its respective drawer hole and tend to flex each pivoted compartment end wall inwardly to grip a drawer to retain it therein, cardboard drawers each contained within its respective drawer compartment and insertable through its respective drawer hole, and knob means for said drawers.

3. A compartment box, comprising a continuous cardboard cover comprising a base, a rear wall projecting integrally upwardly from said base, side walls projecting integrally laterally and upwardly from said base, a front wall projecting integrally forwardly and upwardly from said base having a plurality of tiers of drawer holes therein and a top projecting integrally forwardly from said front wall and over said box of a length to abut the upper end of said rear wall, a plurality of oblong hollow drawer compartments 35 of substantially the size of said drawer holes, and depth of said box, each comprising a continuous piece of cardboard infolded to form a base, integral end wall, integral top and integral freely pivotable opposite end wall arranged within said cover with the hollow front portion of each one substantially opposite its respective drawer hole and layers of corrugated board interposed horizontally and vertically between said cover base, top and end walls and each respective compartment base, top and end walls and means to bind said cover around the walls of said box to retain said compartments and layers together, 40 said spacing layers being of a sufficient number that when said cover and binding means are attached around said drawer compartments, said layers may be compressed to accurately retain each respective drawer compartment permanently opposite its respective drawer hole and tend to flex each pivoted compartment and wall inwardly to grip a drawer to retain it therein, cardboard drawers each contained within its respective drawer compartment and insertable through its respective drawer hole and knob means for said drawers.

4. A compartment box, comprising a continuous cardboard cover comprising a base, a rear wall projecting integrally upwardly from said base, side walls projecting integrally laterally and upwardly from said base, a front wall projecting integrally forwardly and upwardly from said base having a plurality of tiers of drawer holes therein at least one of said tiers having a plurality of horizontally aligned drawer holes therein and a top projecting integrally forwardly from said front wall and over said box of a length to abut the upper end of said rear wall, a plurality of oblong hollow drawer compartments of substantially the size of said drawer holes, and depth of said box, each comprising a continuous piece of cardboard infolded to form a base, integral end wall, integral top and integral freely pivotable opposite end wall arranged within said cover with the hollow front portion of each one substantially opposite its respective drawer hole, layers of compressible strip spacing material interposed horizontally and vertically between said cover base, top and end walls and each respective compartment base, top and end walls and means to bind said cover around the walls of said box to retain said compartments and layers together, 50 said spacing layers being of a sufficient number that when said cover and binding means are attached around said drawer compartments, said layers may be compressed to accurately retain each respective drawer compartment permanently opposite its respective drawer hole and tend to flex each pivoted compartment end wall inwardly to grip a drawer to retain it therein, cardboard drawers each contained within its respective drawer compartment and insertable through its 55 top.

wall, integral top and integral freely pivotably opposite end wall arranged within said cover with the hollow front portion of each one substantially opposite its respective drawer hole, layers of corrugated board of different thickness interposed horizontally and vertically between said cover base, top, and end walls and each respective compartment base, top and end walls and means to bind said cover around the walls of said box to retain said compartments and layers together, 10 said spacing layers being of a sufficient number and individual thickness that when said cover and binding means are attached around said drawer compartments, said layers may be compressed to accurately retain each respective drawer compartment permanently opposite its respective drawer hole and tend to flex each pivoted compartment end wall inwardly to grip a drawer to retain it therein, cardboard drawers each contained within its respective drawer compartment and insertable through its 15 top centrally thereof, cardboard strips of greater area than the drawer front walls secured thereto for air and dust sealing purposes and to limit the rearward movement of said 20 drawers also having a hole centrally thereof, knob means for said drawers, each comprising a base having a tapered shank projecting outwardly through each drawer hole and a knob handle having a boss projecting rearwardly therefrom 25 adapted to abut the front of each drawer around said hole having a hole therein for frictionally retaining said tapered shank therein, supplemental cardboard strips secured to the top and bottom of said box of greater area than the top and bottom 30 of said box, whereby a supplemental wrapper may be wrapped around said box exterior of said knob means and a plaque adapted to contain advertising matter thereon distinctive of each individual vendor supplementally secured to the 35 top of said box.

5. A compartment box, comprising a continuous cardboard cover comprising a base, a rear wall projecting integrally upwardly from said base, side walls projecting integrally laterally and 40 upwardly from said base, a front wall projecting integrally forwardly and upwardly from said base having a plurality of tiers of drawer holes therein and a top projecting integrally forwardly from said front wall and over said box of a length to 45 abut the upper end of said rear wall, a plurality of oblong hollow drawer compartments of substantially the size of said drawer holes, and depth of said box, each comprising a continuous piece of cardboard infolded to form a base, integral end wall, integral top and integral freely 50 pivotable opposite end wall arranged within said cover with the hollow front portion of each one substantially opposite its respective drawer hole, layers of compressible strip spacing material interposed horizontally and vertically between said 55 cover base, top and end walls and each respective compartment base, top and end walls and means to bind said cover around the walls of said box to retain said compartments and layers together, 60 said spacing layers being of a sufficient number that when said cover and binding means are attached around said drawer compartments, said layers may be compressed to accurately retain each respective drawer compartment permanently 65 opposite its respective drawer hole and tend to flex each pivoted compartment end wall inwardly to grip a drawer to retain it therein, cardboard drawers each contained within its respective drawer compartment and insertable through its 70 top.

75

respective drawer hole having a hole centrally thereof, knob means for said drawers, each comprising a base having a tapered shank projecting outwardly through each drawer hole and a knob handle having a boss projecting rearwardly therefrom adapted to abut the front of each drawer around said hole having a hole therein for frictionally retaining said tapered shank therein.

6. A cover for use in making compartment boxes comprising, a continuous cardboard sheet comprising a base, a rear wall adapted to be bent integrally upwardly from said base, side walls projecting integrally laterally adapted to be bent upwardly from said base, a front wall projecting integrally forwardly and adapted to be bent upwardly from said base having a plurality of tiers of drawer holes therein at least one of said tiers having a plurality of horizontally aligned drawer holes therein and a top projecting integrally forwardly from said front wall adapted to be bent inwardly from said front wall to form the top of a length when so infolded to abut the upper end of said infolded rear wall.

7. A cover for use in making compartment boxes comprising a continuous cardboard sheet comprising a base, a rear wall adapted to be bent integrally upwardly from said base, side walls projecting integrally laterally adapted to be bent upwardly from said base, a front wall projecting integrally forwardly and adapted to be bent upwardly from said base having a plurality of tiers of drawer holes therein and a top projecting integrally forwardly from said front wall adapted to be bent inwardly from said front wall to form the top of a length when so infolded to abut the upper end of said infolded rear wall.

8. A compartment box, comprising a continuous cardboard cover comprising a base, a rear wall projecting integrally upwardly from said base, side walls projecting integrally laterally and upwardly from said base, a front wall projecting integrally forwardly and upwardly from said base having a plurality of tiers of drawer holes therein and a top projecting integrally forwardly from said front wall and over said box of a length to abut the upper end of said rear wall, a plurality of oblong hollow drawer compartments of substantially the size of said drawer holes, and depth of said box, each comprising a continuous piece of cardboard infolded to form a base, integral end wall, integral top and integral freely pivotable opposite end wall arranged within said cover with the hollow front portion of each one substantially opposite its respective drawer hole, layers of corrugated board interposed horizontally and vertically between said cover base, top, and end walls and each respective compartment base, top and end walls and means to bind said cover around the walls of said box to retain said compartments and layers together, said spacing layers being of a sufficient number that when said cover and binding means are attached around said drawer compartments, said layers may be compressed to accurately retain each respective drawer compartment permanently opposite its respective drawer hole and tend to flex each pivoted compartment end wall inwardly to grip a drawer to retain it therein.

9. A compartment box, comprising a continuous cardboard cover comprising a base, a rear wall projecting integrally upwardly from said base, side walls projecting integrally laterally and upwardly from said base, a front wall projecting integrally forwardly and upwardly from said base having a plurality of tiers of drawer holes

therein and a top projecting integrally forwardly from said front wall and over said box of a length to abut the upper end of said rear wall, a plurality of oblong hollow drawer compartments of substantially the size of said drawer holes, and depth of said box, each comprising a continuous piece of cardboard infolded to form a base, integral end wall, integral top and integral opposite end wall arranged within said cover with the hollow front portion of each one substantially opposite its respective drawer hole and layers of corrugated board interposed horizontally and vertically between said cover base, top, and end walls and each respective compartment base, top and end walls and means to bind said cover around the walls of said box to retain said compartments and layers together, said spacing layers being of a sufficient number that when said cover and binding means are attached around said drawer compartments, said layers may be compressed to accurately retain each respective drawer compartment permanently opposite its respective drawer hole.

10. An assembly for use in the manufacture of compartment boxes comprising a plurality of oblong hollow drawer compartments, each comprising a continuous piece of cardboard infolded to form a base, integral end wall, integral top and integral freely pivotable opposite end wall arranged in a plurality of tiers in parallel formation with each drawer compartment having an open front and rear end, layers of corrugated board arranged horizontally between each tier and on top of the upper tier and below the bottom of the bottom tier and arranged vertically at the ends of each tier to build up an assembly of slightly greater size than the desired size of the completed box and means to bind said layers together around said compartments to compress them to substantially the desired size of the box.

11. A compartment box, comprising a continuous cardboard cover comprising a base, a rear wall projecting integrally upwardly from said base, side walls projecting integrally laterally and upwardly from said base, a front wall projecting integrally forwardly and upwardly from said base having a plurality of tiers of drawer holes therein and a top projecting integrally forwardly from said front wall and over said box of a length to abut the upper end of said rear wall, a plurality of oblong hollow drawer compartments of substantially the size of said drawer holes, and depth of said box, each comprising a continuous piece of cardboard infolded to form a base, integral end wall, integral top and integral opposite end wall arranged within said cover with the hollow front portion of each one substantially opposite its respective drawer hole, layers of compressible strip spacing material interposed horizontally and vertically between said cover base, top and end walls and each respective compartment base, top and end walls and means to bind said cover around the walls of said box to retain said compartments and layers together, said spacing layers being of a sufficient number that when said cover and binding means are attached around said drawer compartments, said layers may be compressed to accurately retain each respective drawer compartment permanently opposite its respective drawer hole, and cardboard drawers each contained within its respective drawer compartment and insertable through its respective drawer hole and knob means for said drawers.

12. A compartment box, comprising a continu-

ous cardboard cover comprising a base, a rear wall projecting integrally upwardly from said base, side walls projecting integrally laterally and upwardly from said base, a front wall projecting integrally forwardly and upwardly from said base having a plurality of tiers of drawer holes therein and a top projecting integrally forwardly from said front wall and over said box of a length to about the upper end of said rear wall, a plurality of oblong hollow drawer compartments of substantially the size of said drawer holes, and depth of said box, each comprising a continuous piece of cardboard infolded to form a base, integral end wall, integral top and integral opposite end wall arranged within said cover with the hollow front portion of each one substantially opposite its respective drawer hole and layers of corru-

gated board interposed horizontally and vertically between said cover base, top, and end walls and each respective compartment base, top and end walls and means to bind said cover around the walls of said box to retain said compartments and layers together, said spacing layers being of a sufficient number that when said cover and binding means are attached around said drawer compartments, said layers may be compressed to accurately retain each respective drawer compartment permanently opposite its respective drawer hole, and cardboard drawers each contained within its respective drawer compartment and insertable through its respective drawer hole and knob means for said drawers.
